UNITED STATES PATENT OFFICE.

HENRY J. FREDERICK, OF HOOD RIVER, OREGON.

LOCKING DEVICE FOR DOORS AND WINDOWS.

1,082,019.

Specification of Letters Patent.

Patented Dec. 23, 1913.

Application filed March 27, 1913. Serial No. 757,284.

To all whom it may concern:

Be it known that I, HENRY J. FREDERICK, a citizen of the United States, residing in the town of Hood River, county of Hood River, and State of Oregon, have invented 5 certain new and useful Improvements in Locking Devices for Doors and Windows, of which the following is a specification.

My invention relates to locking devices 10 for doors and windows, and more particularly to a simple, little device of the character referred to which can be carried in the pocket, pocket book, or on a key ring with keys, and, if desired, can be used as a name 15 plate for identification purposes, but it is especially designed and adapted for use in locking a door or window against being opened.

The principal object of the invention is to 20 provide a device of the character referred to of such small dimensions that it can be very conveniently carried at all times, as is a small key, and of such construction that it is complete in itself and capable of being applied to any door or window without the attachment or detachment of any other part or device, and without the use of any tools whatsoever.

Broadly considered, the invention comprises 25 a device of thin plate like construction adapted to be inserted between the two parts or members to be locked together, as between the door frame and a door, or between two window sashes at their meeting 30 edges, with a part adapted to be turned crosswise thereof, whereby to engage the face or edge of the door or sash and prevent its being moved away from the other part until the movable part of the device has 35 been turned into the same plane of the device.

In order that others may understand my 40 invention, and its application, I have shown in the accompanying sheet of drawings, one 45 practical form or embodiment thereof, and one use for which it is especially adapted.

In the drawings,—Figure 1 is a face view 50 of a practical form of the invention; Fig. 2 is an end view thereof, with a part turned crosswise thereof; and Fig. 3 is a fragmentary cross sectional view through a door frame and a door, showing the invention in 55 operating position.

The invention here shown and which I 60 will now describe, comprises a plurality of plate members, 1 and 2, hinged together, as

at 3, to turn upon an axis extending longitudinally of the device, one of said members being provided with one or more prongs, as 4—4, and the other member being provided 60 with a hole, as 5, by means of which said device can be placed on a key ring, or hung upon a nail or hook, as may be desired. The member 2 is adapted to be turned in either direction at right angles to or cross- 65 wise of the member 1, as indicated in dotted lines in Fig. 2, and as shown in full lines in Fig. 3. The inner end of said member 1 is straight and stands in alinement with the inner end of the hinge bead, as at 6, whereby 70 said hinge bead is adapted to serve as a gage in applying the device to the door or window.

In Fig. 3, 7 designates a part of a door frame, and 8 the edge of a door, the invention being placed between the meeting surfaces thereof in the manner indicated, to prevent the door from being opened. 75

The operation of the device may be briefly described as follows: Before the door is 80 closed, the device is placed against the door frame with the hinge bead 3 resting against the face thereof, or against that part of the door frame which rests flush with the face of the door when the latter is closed. The 85 members 1 and 2 of the device, it will be understood, stand in the same plane when it is applied to the door. As the door is closed, the prongs 4—4 are forced into the door frame in the manner indicated. When the 90 door is thus fully closed, its face is flush with the part of the frame against which the hinge bead was placed, and the part 2 of the device is then turned crosswise of the member 1, in the manner shown in full lines, Fig. 95 3, so that its inner, or square end rests against the face of the door and prevents the door from being opened until the part 2 is turned back to a position in the same plane with the part 1. If desired, the de-

vice can be placed lower down on the door, as at the lock, with the prongs thereof inserted into the bolt-receiving socket in the face of the door frame, and which is indicated in dotted lines in Fig. 3. This prevents the penetration of the door frame by the prongs 4—4, as will be readily understood. 100 105

While I have shown and described one practical embodiment of the invention for 110 purposes of illustration, I am aware that modifications can be made therein without

departing from the spirit thereof, and I do not, therefore, limit the invention to the particular form here shown, except as I may be limited by the hereto appended claims.

5. What I claim and desire to secure by Letters Patent is,—

1. A locking device of the character referred to, comprising a two-part plate member, one part of which is provided with one or more prong-like members, and the other part of which is adapted to be turned crosswise of the other part on an axis extending longitudinally thereof, for the purpose referred to.
10. 2. A locking device of the character referred to, comprising two plate members hinged together in the same plane, upon an axis extending longitudinally thereof, one of said members being provided with one or more prong members projecting at an angle therefrom, and the other of said members being adapted to be turned crosswise thereof upon an axis extending longitudinally of the device, for the purpose illustrated.
15. 3. In a door locking device of the character referred to, a plurality of plate members hingedly secured together in the same plane, one of said members being provided with

one or more laterally projecting prongs, and another of said members being adapted to be turned crosswise, longitudinally of their lengths, of said first member and having a straight engaging end standing at right angles to the plane of said first member, substantially as described.

35. 4. In a locking device of the character referred to, two plate members hinged together to turn upon an axis extending longitudinally of said device for a portion of its length only and forming a hinge bead upon said device, one of said members being provided with laterally projecting prongs on the side of said bead, and the other of said members having a straight end in alinement with the inner end of said hinge bead, and adapted to be turned crosswise of said first member, substantially as shown and described.

In witness whereof, I have hereunto set my hand at Portland, Oregon, this 21st day of March, 1913.

HENRY J. FREDERICK.
